FOLDED BLANK CONTAINER FOR
CIGARETTES AND THE LIKE

Louis I. Lane, Miami Beach, Fla.

Application September 2, 1948, Serial No. 47,480

3 Claims. (Cl. 229—27)

1

This invention relates to a container for cigarettes or the like which provides two compartments or sections for the reception of the goods. The container is formed from a single sheet of suitable material which may be folded to provide two separate sections, each section having a unique way of supporting the cigarettes or the like contained therein.

It is the primary object of this invention to provide a container for cigarettes and the like that is convenient for the user to carry and use, durable, simple and inexpensive to construct and has the necessary sanitary conditions for carrying such goods as cigarettes.

A further object of this invention is to construct a container having a dual compartment for the reception of goods, such as cigarettes, cigars, candy or any other article having a shape similar to that of a cigarette, wherein the user is able to carry more than the ordinary number of such articles with him at all times and which provides a means for compactly and tightly arranging the goods in each compartment so that the goods will remain in an upright position and be enjoined from falling out of said compartments.

It is a still further object of this invention to provide a container for cigarettes and the like which is made from one complete piece of foldable and durable material, which provides dual compartments for the reception of the goods, which provides a means for enjoining the goods from falling out of the compartment no matter in what position the container is placed and which has means to firmly secure the compartments together as a unit thereby providing a light, convenient and durable means for packaging such goods.

To enable others skilled in the art to more fully comprehend the underlying features of my invention, reference is made to the accompanying drawing which forms a part of this specification and in which:

Figure 1 is a front elevational view of the container in its closed position.

Figure 2 is a side elevational view of the container in its closed position.

Figure 3 is a front elevational view showing the inside of the container in its open position.

Figure 4 is a sectional view taken along the lines 4—4 of Figure 3.

Figure 5 is a view showing the shape of the sheet of material used to form the instant container.

In referring to the drawings in detail, wherein like characters designate corresponding parts

2

throughout the several views, 1 represents the container in its closed position. The dual compartments 2 and 3 each comprise outer side portions 5 and 6, a common base 7 and inner side portions 8 and 9. The inner side portions 8 and 9 have at the top of their faces arcuately shaped edges 10 and 11 to provide convenience in removing the cigarettes or cigars or the like 12 from the container when the container is in its open position. The entire container is formed from a single sheet of suitable material, as shown in Figure 5 and this material may be cardboard or any other stiff material which is customarily used for the purpose of packaging goods.

15 Referring particularly to Figures 1, 2, 3 and 4, it will be noted that the outer side portion 5 is provided with a flap 13 and that the outer face 6 is provided with a slit 14 as shown in Figure 1. The inner side portion 8 is provided with a cut-away portion 15 which corresponds in size to the overlapping flap 13. Therefore, it can be seen that the flap 13 is adapted, by means of inserting this flap in the slit 14, to secure the compartments 2 and 3 together, thereby maintaining the container in a closed position. Each compartment is provided with a top portion 16 and it should be noted that the flap 13 is formed from the cut-away portion of the inner side portion 8 and the top portion 16.

15 Each of the inner side members 8 and 9 are provided with slits 17 which are adapted to receive the extensions 18 of the outer side portions 5 and 6. By particularly referring to Figures 3, 4 and 5, it can be seen that the extensions 18 are provided with V-shaped cut-away portions 19 and overlapping flaps 20. By folding the flaps 20 a support is formed for the cigarettes 12 as shown more clearly in Figures 3 and 4. It can be seen by particularly referring to Figures 3 and 5 that the extensions 18 have one part 21 which provides end portions or walls for each compartment 2 and 3 and another part 22 which is inserted in the slits 17 with the flaps 20 being folded inwardly substantially adjacent to and parallel with said common base. The parts 22 which include the folded flaps 20 are adapted to be received in the slits 17 of the inner side portions 8 and 9 and are interlocked therein by means of the cut-away portions 19. The parts 22 as shown in Figure 3 come together in abutting relationship at 24 and are held in that position by means of the interlocking engagement of the cut-away portions 19 and the slit 17. The overlapping flaps 20 provide a substantially continuous support, extending substantially the length of each

30 35 40 45 50 55

section, for the cigarettes 12 as shown in Figures 3 and 4.

By referring to Figure 5 of the drawing, it can be seen that parts 8 and 9, 16, 5 and 6 and 7 are hingedly connected along parallel side fold lines, that extensions 18 are hingedly connected along their fold lines to parts 5 and 6, that parts 21 and 22 of each extension are hingedly connected together and that the flaps 20 are hingedly connected along side fold lines to parts 22 of the extensions.

In view of the above detailed description, it can be seen that by properly folding the sheet of material shown in Figure 5 and by inserting part of the extensions 18 in the slits 17 of the side portions 8 and 9, a container is formed which is durable, provides a support for the goods contained in each of the two compartments, is simple and inexpensive to construct and is convenient for many uses.

While I have shown and described my invention with some degree of particularity, it is to be realized that other modifications and changes may be resorted to under certain conditions. Therefore, I do not feel that it is necessary to limit myself to the precise construction set forth but consider it permissible to make slight changes and alterations which fall within the spirit and scope of the invention.

Having shown and described my invention, what I claim as new and desire to secure by Letters Patent is:

1. A container for cigarettes and the like formed from a single sheet of material, said sheet being folded to provide two sections for the reception of cigarettes, said sections having a common base, each of said sections having a top portion, and inner and outer side portions, slits in said inner side portions, said outer side portions each having a pair of extensions, each extension having two parts, one part of each extension forming an end portion of its respective section and the other part of each extension having a foldable flap, said latter part of each extension being inserted through one of said slits in said inner side portions with said flap being folded inwardly substantially adjacent to and parallel with said common base, said flaps of each pair of extensions forming a substantially continuous tension means extending substantially the length of each section for supporting the cigarettes in an upright position.

2. A container for cigarettes and the like formed from a single sheet of fibrous material, said sheet being folded to provide two sections for the reception of cigarettes, said sections having a common base, each of said sections having a top portion, and inner and outer side portions, slits in said inner side portions, said outer side portions each having a pair of extensions, each extension having a V-shaped cut-away portion that divides the extension into two parts, one part of each extension forming an end portion of its

respective section, the other part of each extension having a foldable flap, said latter part of each extension being inserted through one of said slits in said inner side portions with said flap being folded inwardly substantially adjacent to and parallel with said common base, means including said V-shaped cut-away portion for holding the end of said latter part of one extension of each side portion in abutting relationship with the end of the latter part of its other extension, said flaps of each pair of extensions forming a substantially continuous tension means extending substantially the length of each section for supporting the cigarettes in an upright position, and means including an additional flap overlapping said top portions for securing said sections together.

3. A blank for a container having two sections for the reception of cigarettes comprising a common base member, an outer side member for each section hingedly connected to said base member along parallel side fold lines, a top member for each section hingedly connected along parallel side fold lines to the outer side members, an inner side member for each section hingedly connected to each of said top members along side fold lines, said inner members having slits therein, an extension hingedly connected to each end of said inner members along parallel end fold lines, each extension having a cut-away portion that divides the extension in two parts that are hingedly connected to each other, one part of each extension being adapted to form an end portion of its respective section, the other part of each extension having hingedly connected thereto along a side fold line a foldable flap, said other part of each extension being insertable through one of the slits in said inner side members with said flap being adapted to be folded inwardly substantially adjacent and parallel with said common base, said cut-away portion being adapted to hold the end of the part of one extension in abutting relationship with the end of the other part of another extension when the extensions of each outer side member are inserted in said slits, said flaps of each pair of extensions forming when folded a substantially continuous tension means extending substantially the length of each section for supporting the cigarettes in an upright position.
